UNITED STATES PATENT OFFICE.

FRANCIS K. HOLMESTED, OF CHARLESTON, WEST VIRGINIA.

COAL CUTTING AND LOADING MACHINE.

Application filed October 3, 1922. Serial No. 592,057.

To all whom it may concern:

Be it known that I, FRANCIS K. HOLMESTED, a subject of the King of Great Britain, residing at Charleston, in the county of 5 Kanawha and State of West Virginia, U. S. A., have invented certain new and useful Improvements in Coal Cutting and Loading Machines, of which the following is a specification.

10 This invention relates to cutting and loading machines adapted for service in mines for cutting and loading coal or other similar material having a natural veinous, ledge or analogous accessible formation.

15 The present machine has been particularly devised for cutting and loading coal and constitutes an improvement on the machine disclosed by my pending application filed January 3, 1920, Serial No. 349,210.

20 The object of the improved mechanism is to cut coal from the face of a vein by a longitudinal movement of the mechanism, which is disposed to travel the full length of the vein and to perform the cutting operation rectilinearly relatively to the vein and automatically load the coal after it is cut, and thereby complete the mining operation without resorting to other auxiliary appliances.

25 The present improved machine is essentially distinguished from the machine disclosed by my pending application above noted in that the cutting mechanism moves at all times in a straight line instead of

30 arcuately swinging, the operation, however, in the improved machine being effected in a horizontal plane at various elevations by adjustment of the cutting mechanism.

35 The improved machine propels itself by 40 self-contained power along the track adjacent to a mine wall, and starting at one end of the wall or vein of coal, cuts a horizontal kerf at any elevation desired along the entire length of the wall. The machine 45 is then returned under its own power to the starting point and the cutting receiver raised or lowered as desired and the cutting operation similarly repeated. After 50 the cuts have been made from top to bottom of a seam, the cutting receiver carried on the outer end of the delivery conveyor frame is so mounted as to be advanced further into the vein and the vein again cut from top to bottom along the entire length 55 of the mine wall. This operation may be repeated until the receiving conveyor has

been advanced to its maximum distance relatively to the adjustment or adjacency of the track rails to the mine wall and upon which the machine as a whole is mounted 60 to operate. When the maximum extension of the cutting mechanism has been reached and the cutting operation completed, the conveyor carrying the cutting mechanism including a receiver is run back to close cutting position and the track then adjusted or slewed over to a position along the face of the mine wall or vein, so that the cutting receiver will again engage the vein and the 65 operation of cutting repeated throughout 70 the length of the vein.

The coal is cut from the vein in the form of half columns by means of cutting mechanism similar to that disclosed in my pending application, and the cut coal passes into 75 the cutting mechanism and receiver forming part of the latter and is engaged by a breaker at regular intervals to set up a fracture of the cut columns relatively to the vein from which they are cut. During this 80 breaking operation the coal continues to pass through the receiver and drops free and is held by said receiver and expelled or pushed out from the latter by the incoming or successive charges of coal, the coal being 85 deposited on the conveyor mounted at the rear side of the receiver, and from the latter the coal is carried by the conveyor to a hopper car, from which it is in turn delivered to a mine car. 90

In the drawings:

Fig. 1 is a top plan view of part of a coal cutting or loading machine embodying the features of the invention and which is to be applied to the top portion of Fig. 1; 95

Fig. 1^a which is to be applied to the top portion of Fig. 1 is a top plan view of a part of the conveyor and the cutting mechanism carried thereby and including the receiver;

Fig. 1^b is a top plan view of a continuation of part of the loading mechanism and from which the cut coal is delivered into the mine car and applicable to the left extremity of Fig. 1; 100

Fig. 2 is an elevation of the inner side of 105 a portion of the machine;

Fig. 2^a is a side elevation of a part of the loading mechanism to be applied to the right-hand extremity of Fig. 2;

Fig. 3 is a rear side elevation of the receiver and conveyor together with part of 110 the mechanism cooperating therewith;

Fig. 4 is a section on the line 4—4, Fig. 3, on an enlarged scale; and

Fig. 5 is a detail section on the line 5—5, Fig. 1^a;

Fig. 6 is an outline plan view on a reduced scale showing the entire machine and its relation to the wall of material to be cut and also its rectilinear movement.

The main support of the improved machine consists of a receiving hopper or hopper car 5 provided with suitable axles 6 and flanged track wheels 7 to engage track rails 8 and freely movable over the latter. The hopper or hopper car 5 is shaped similarly to coal hoppers, but in the present instance has a permanently closed bottom portion 9 which is horizontally extended over the axles 6 to provide a supporting frame 10 under the inclined ends 11 of the hopper for various mechanical devices which will be presently explained. Secured to the bottom 9 of the hopper on opposite sides of the center are guide beams 12 having the inner opposed sides formed with grooves 13 to loosely and movably receive correspondingly shaped side flanges 14 of a sliding frame 15, which is preferably of open structure as shown by Fig. 1, or has side bars 16 connected and reinforced as, for instance, by a cross bar 17, it being intended to construct the frame 15 in such strong and durable manner as to resist the strain imposed thereon during the operation of the improved mechanism. The guide beams 12 are also connected by a cross member 18, which serves as a means for mounting a screw shaft 19 swiveled in the said member 18, as at 20. The screw threads 21 of the shaft 19 engage the cross bar 17 of the frame 15 to feed the latter frame forwardly and rearwardly in accordance with the direction of rotation of the said shaft. The threads 21 are formed on the shaft 19 a distance which will permit maximum forward and rearward movements of the frame 15 in accordance with a predetermined arrangement. On the frame 10 under the rear inclined ends of the hopper or hopper car 5 is a suitable electric motor 22 having its armature shaft 23 projected laterally, or towards the outer side of the said hopper a sufficient distance to operatively receive a sprocket wheel 24, and on the same frame 10 at a distance from the motor and further under the adjacent inclined end of the hopper 5 a drive shaft 25 is also mounted in suitable bearings and provided with a sprocket wheel 26 in alinement with the sprocket wheel 24 on the said armature shaft 23, the two sprocket wheels 24 and 26 being engaged by, or having trained thereover, an endless chain belt 27. The drive shaft 25 extends completely across the supporting frame 10 and outwardly a short distance at each end 65 beyond the front and rear side of the hopper

or hopper car 5, and on its rear end is loosely mounted a sprocket wheel 28 having a clutch member 29, and adjacent to the latter member and keyed to the said shaft 25 to rotate therewith is a sliding clutch member 30 which is operated by suitable lever mechanism 31 projecting outwardly and upwardly along the rear side of the hopper 5 to throw the said sprocket wheel 28 into and out of operative connection with relation to the shaft 25. On the rear end of the screw shaft 19 is a sprocket wheel 32, and over the sprocket wheels 28 and 32 an endless chain belt 33 is applied whereby the said screw shaft may be regularly driven as found necessary for operating the slide frame 15. The drive shaft 25 also has a pinion 34 loosely mounted thereon and held in continual engagement with a gear 35 keyed to the adjacent axle 6. The pinion 34 is provided at its rear side with a clutch member 36, and keyed to the shaft 25 and slidable thereon by suitable lever mechanism 37^a is a clutch collar 37 which is adapted to engage the clutch member 36 of the pinion 34 and transmit the motion of the shaft 25 to the said pinion 34 and from the latter to the gear 35 to drive the axles 6 and cause the hopper or hopper car 5 to move in opposite directions over the track rails in accordance with the reverse movements of the armature shaft 23 of the motor 22, said reverse movements being effected by well known means in this class of motors.

On the inner side of the upper portion of the hopper or hopper car 5 a bracket support 38 is secured and has depending bearings 39, in which a short power transmitting shaft 40 is mounted to rotate and carries thereon a gear 41 having side flanges 42, a driving sprocket 43 being secured on the said shaft and in line with a sprocket 44 on the end of the shaft 25 opposite that carrying the sprocket 28, or on the forward end of said shaft 25. Engaging the sprockets or sprocket wheels 43 and 44 is a chain belt 45, and by this connected mechanism the shaft 40 is regularly driven from the shaft 25 to operate the gear 41 at the proper rate of speed. The sprocket wheel 44 has an inwardly projecting clutch member 46, and adjacent to this clutch member a clutch collar 47 is mounted on the shaft 25 and operated by suitable shifting lever mechanism 48 at the side of the hopper or hopper car 5, the clutch collar 47 being keyed to the shaft 25 and adapted to transmit the motion of the latter to the clutch member 46 and operate the sprocket wheel 44 and in turn through the chain or endless belt 45 actuate the sprocket wheel 43 on the shaft 40. Below the shaft 40 and held in suitable bearings 49 and 50 respectively supported by the extension of the bottom 9 of

the hopper or hopper car 5 and the slide frame 15 a power transmitting shaft 51 is mounted and has free sliding movement through the bearing 49, and on this shaft 5 is a slideable pinion 52 which is held in continual mesh with the gear 41 on the shaft 40 above. Mounted on the front extremity of the slide frame 15 and disposed on a suitable cross connecting member 53 thereof 10 is a sprocket 54 fixed to a stub shaft 55 rising from the support 53, the top portion of the sprocket or sprocket wheel 54 being provided with a beveled pinion 56 attached thereto and in continual mesh with a corresponding beveled pinion 57 on the forward end of the shaft 51 in advance of the bearing 50. At a suitable distance in advance of the sprocket wheel 54 and pinion 56 and movably mounted on suitable bearings on 15 the forward ends of the side members of the frame 15 are sprocket wheels 58 and 59 with screw spindles 60 rising from the center of and rotatable with the said sprocket wheels. Engaging or trained over 20 the sprocket wheels 54, 58 and 59 is an endless chain belt 61, and by means of this mechanism the screw spindles 60 are rotated in either one of two directions in accordance with the direction of rotation of the shaft 25 25 controlled by the actuation of the shaft 40 through the sprocket wheel 43 and gear 41 and pinion 52 from the driving shaft 25 by means of a chain belt 45 engaging the sprocket 44 and sprocket 43, the reverse movement being attained by changing the direction of movement of the said shaft 25 through a reversal of the driving motor 22. On the bracket support 38 upright bearings 63 are secured for a roller shaft 64, and 30 projecting inwardly from the upper extremity of each of these bearings 63 is a confining anti-frictional roller 65. The roller shaft 64 and the confining anti-frictional roller 65 are adapted for cooperation 35 with opposite I-beams 66 of a conveyor 67, said I-beams forming the side members of the conveyor 67 and the latter provided with an endless belt 68 having flights 69 at regular intervals and opposite endless 40 chain belts 69^a. As shown by Figs. 2 and 3, side flanges 70 project upwardly from the I-beams 66 forming the side members of the conveyor 67, said flanges serving as guards to prevent overflow of the material passing 45 over the conveyor. Screw collars 71 are secured to the opposite sides of the conveyor, or the I-beams 66, and are freely movable on the screw spindles 60 for the purpose of raising and lowering the conveyor and the 50 parts attached thereto. The bottoms of the lower flanges of the I-beams 66 loosely rest on the opposite ends of the roller shaft 64 between the bearings 63, and the confining anti-frictional rollers 65 are adapted to engage the upper sides of the outer portions 55 of the bottom flanges of the said I-beams, as at 62, to movably retain the conveyor in engagement with the said roller shaft. By assembling the I-beams 66 of the conveyor with the roller shaft 64 as just explained, 60 said conveyor is given a fulcrum mounting, and in addition to free longitudinal sliding movement over the roller shaft, the said conveyor may be freely swung to raise and lower it at varying angles in accordance with 65 the adjustment desired. Through the actuation of the shaft 51 and the bevel pinion 57, the bevel pinion 56 and sprocket wheel 54 will be positively actuated and the movement of the said sprocket wheel 54 is conveyed by the chain belt 61 to the sprocket wheels 58 and 59 and the screw spindles 60 uniformly rotated to equally elevate or depress the opposite sides of the conveyor, the latter then swinging on the roller shaft 64 as above noted. 70

Fixed to the outer end of the conveyor is a tubular or cylindrical receiver 72 having a rear closed end 73, an outer longitudinally straight side 74 and a fully open front end 75. This receiver is essentially similar to the receiver disclosed by my pending application aforesaid with the exception that the outer side wall 74 is longitudinally straight and the inner side wall 76 parallel therewith so far as this latter wall extends from the fully open front end 75. The outer extremity of the conveyor 67 continues over the lower portion of the receiver, the latter being essentially circular in cross section 75 without any break or flattened structure as in my application hereinbefore mentioned, and the inner side is formed with a rear guard flange 77 and an intermediate similar flange 78 on opposite sides of the rear outlet 80 opening 79, the top portion of the receiver being cut out a sufficient distance to give a clearance for the passage of the cut coal or material from the receiver directly onto the outer extremity of the conveyor. In 105 other words, the outer extremity of the conveyor projects a sufficient distance to tangentially intersect the lower arcuate bottom of the receiver 72, as clearly shown by Fig. 3, and by this means a quick release of the cut 110 coal or material from the receiver may be obtained. The guard flanges 77 and 78 also serve to prevent an overflow of the cut coal or material passing through the rear discharge opening 79 of the receiver onto the 115 conveyor belt 68. The receiver 72 in the present instance is also provided with a breaker 80, similar in construction and operation to the breaker disclosed by my application hereinbefore specified and consisting 120 of an oscillating arcuate plate or member 80 fulcrumed at an intermediate point, as at 81, at the upper and lower edges thereof and partially movable through an opening 82 as 125 shown by Fig. 4. A part of this breaker, or 130

the arcuate member 79^a thereof, has an oscillating movement in and through the opening 82 and is projected a sufficient distance within the receiver 72 to set up a pressure 5 on the cut columns of coal and at regular intervals break the latter, or cause a disjunction thereof relatively to the vein from which the successive columns are cut, and by this means a continuous cutting operation 10 may be effected in a straight line throughout the whole length of a vein or seam and the columns broken at intervals to give way for the successive injection of cut and unbroken columns into the receiver. The cut coal or 15 material entering the receiver operates also to push out the preceding charges, or any coal that may remain accumulated in the receiver, the coal from the receiver being pushed through the rear discharge opening 79 onto 20 the conveyor belt 68 and by the latter carried backwardly into the hopper or hopper car. The breaker 80 has a reduced member 83 at its rear end adjacent to and extending partially over the rear end 73 of the receiver, 25 and is continually engaged by a flat spring 84 which operates to press the rear reduced end 83 inwardly towards the rear end of the receiver and the opposite end of the breaker outwardly. As in my application hereinbefore noted, means are provided for giving 30 the breaker a reciprocating movement at predetermined intervals, said means consisting of a vertically reciprocating wedge 85, as shown by Fig. 4, said wedge extending 35 upwardly between the reduced extremity 83 and the adjacent curved rear end 73 of the receiver. The lower end of the wedge is eccentrically attached to a crank disk 86 mounted on the free end of a short counter-shaft 87 held by a bearing 88 at the bottom 40 of one side of the forward extremity of the receiver or by one of the I-beams 66. On the shaft 87 is a worm wheel 89 held in continual mesh with a worm 90 on an extension 45 of the forward shaft 91 mounted between the front ends of the I-beams 66 and carrying as usual suitable sprocket wheels to provide idler means for the endless chain belts 69^a of the conveyor, these belts also 50 engaging suitable sprocket wheels 92 on a motion transmitting shaft 93 between the inner ends of the said I-beams. The one end of the shaft 93 is extended beyond or outside of the one I-beam 66 and has a bevel 55 pinion 94 fixed thereon. This pinion 94 continually meshes with a similar bevel pinion 95 fixed on a counter-shaft 96 extending along the same side of the conveyor and terminating adjacent to the rear side 60 of the receiver 72, as shown by Fig. 1^a. The shaft 96 extends adjacent to the bevel pinion 94 beyond its bearing 97 secured to the I-beams 66 and also in an angle bearing comprising transverse and longitudinal members 65 98 and 99 having the said longitudinal mem-

ber mounted to swing. The shaft 96 is formed with a longitudinal groove 100 extending full length of the same and at its forward extremity said shaft is mounted in a bearing 101 similar to the rear bearing 97 70 therefor, the bearing 101 being secured to the adjacent part of the side of the conveyor where the intermediate guard flange 78 is located. On the shaft 96 adjacent to the angle bearing comprising the members 75 98 and 99 is a bevel pinion 102 which has a suitable feather or key to engage the groove 100 of the said shaft, and whereby the shaft is permitted to slide through this bevel pinion 102 when the conveyor 68 is adjusted inwardly and outwardly. The swinging adjustment of the conveyor is not obstructed by this gear mounting, in view of the fact that the angle bearing comprising the members 98 and 99 is mounted to swing in a manner 80 95 which will now be explained.

On the supporting frame 10 forming a continuation of the bottom of the hopper or hopper car 5 opposite that upon which the motor 22 is mounted, a supplemental independently operating motor 103 is disposed and has its armature shaft 104 projecting outwardly and provided with a sprocket wheel 105. On the upper front portion of the side of the hopper or hopper car 5 to the right of the conveyor, bearings 106 are secured and have a power transmitting shaft 107 mounted therein, the outer end of this latter shaft being provided with a sprocket wheel 108, and over the latter sprocket wheel 100 and the sprocket wheel 105 on the armature shaft 104 an endless chain or sprocket belt 109 is trained to convey the power of the supplemental motor 103 to the shaft 107. The longitudinal member 99 of the angle 105 bearing comprising the transverse member 98 is mounted to swing or pivot on the shaft 107 at a distance inwardly from the innermost bearing 106, and on the inner terminal of this shaft 107 inside of the longitudinal member 99 a bevel pinion 110 is fixed and held in continual mesh with the bevel pinion 102 through which the shaft 96 is free to slide. By this supplemental mechanism including the motor 103, the 110 shaft 96 is rotated and the conveyor 68 regularly actuated in a direction to transfer the coal or cut material from the receiver 72 into the hopper or hopper car 5.

The cutting mechanism is carried by and 115 forms part of the receiver 72 and consists of a fully open ring cutter 111 having teeth 112 projecting from the edge thereof and removably held in the ring 111 by set screws 113. The ring 111 has gear teeth 114 cut 120 therein fully around the same for driving purposes, and as shown by the detail section Fig. 5, the ring 111 is rotatably secured to the receiver by a split ring or band 115 which 125 is of the shape shown in this section and 130

secured by fastening devices 116 to the adjacent part of the receiver, so that the ring may have free rotating movement. The mechanism for continuously rotating the cutting ring or member 111 consists of a pinion 117 mounted on the outer end of a short counter shaft 118 held in bearings 119 secured to the rear side 76 of the receiver. On the rear end of the shaft 118 is a bevel pinion 120 which is held in continual mesh with a bevel pinion 121 on the outer end of the shaft 96. By this mechanism it will be perceived that the cutting mechanism forming part of the receiver will be regularly rotated to cause the teeth 112 thereof to sever or kerf the coal or other material operated upon by the improved mechanism.

The hopper or hopper car 5 has at its rear end an upwardly inclined discharge extension 122, as shown in part by Figs. 2 and 2^a, the said extension merging into a horizontally disposed extremity 123 which stands far enough away and at such a distance above the hopper to permit a mine car to be run thereunder to receive the cut coal from the hopper or hopper car 5. Movable over the extension 122 and its horizontal extremity 123 is a discharge conveyor 124, which continues downwardly at an angle towards the interior of the bottom portion of the hopper and engages a guide shaft 125 and sprockets 126 and then continues over through the opposite end of the hopper and engages idler sprockets 127 on a shaft 128 held in suitable bearings as at 129, (see Fig. 2), secured to the adjacent upwardly inclined bottom wall of the hopper. The discharge conveyor 124 as shown by Fig. 1 has flights 130 arranged at regular intervals thereover and also endless chain belts 131 at opposite sides which engage the sprockets 126 and 127 and also sprockets 132 on a power transmitting shaft 133 mounted in the end of the horizontal extremity 123, as clearly shown by Fig. 1^b. The shaft 133 is projected at one side of the extension 123 and has thereon a sprocket wheel 134 which is engaged by an endless chain belt 135 which extends down to and also engages a sprocket 136 mounted on a short transmitting shaft 137 held by a suitable bearing 138 attached to the rear side of the hopper or hopper car 5, the shaft 137 having on its outer end a sprocket 139 engaged by an endless chain or sprocket belt 140, which runs under the adjacent portion of the hopper and over a sprocket 141 loosely mounted on the shaft 25 and having a clutch member 142. The motion of the shaft 25 is transmitted to the clutch member 142 and the sprocket 141 by a clutch collar 143 shiftable on the said shaft but held in rotatable engagement with the latter, the shifting adjustment of this clutch collar 143 being accomplished through lever devices 144 operable at the adjacent side of the hopper or

hopper car 5. By the mechanism just explained the conveyor 124 may be operated and continues to operate to discharge the contents of the hopper or hopper car 5 when the remaining mechanism may be inoperative by disconnecting the remaining clutch devices on the shaft 25 from the operating gears and sprockets, and whereby the loading operation relatively to mine cars that may be positioned successively under the extension 122 and its horizontal extremity 123 may be rapidly effected.

In placing the improved machine for operation, the track rails 8 are disposed such distance from the mine wall or vein or seam to be operated upon as to permit the receiver 72 and conveyor 67 to have a minimum projection, the said receiver and conveyor being adjusted rearwardly by the mechanism hereinbefore described and through the operation of the driving or power shaft 25. The hopper or hopper car 5 is then run back to a starting point and the open cutting end of the receiver 72 brought into engagement with the coal seam or vein at the elevation desired to start the cutting operation and the ring 111 is actuated, and at the same time that the receiver moves lengthwise of the seam or vein the hopper or hopper car 5 synchronously moves through the medium of the power shaft 25, and this operation continues until the cutting operation has been effected throughout the full length of the vein or seam. During the cutting of the coal from the vein or seam, the cut coal enters the receiver 72 in columns and is broken at intervals and discharged from the receiver 72 through the rear discharge outlet 79 onto the conveyor 68 and by the latter transferred to the hopper or hopper car 5 and falls onto the conveyor 124 and by the latter carried rearwardly and upwardly and discharged into a mine car that has been disposed under the discharge extension 122 and its horizontal extremity 123, the operation of the conveyor 124 being effected either after a certain amount of cut coal has been delivered into the hopper or hopper car 5 or at the same time the cutting ring 111 is actuated. These several operations of the parts of the device are readily controllable through the clutch collars and sprockets carrying clutch members, which are all mounted on the shaft 25. As hereinbefore specified, the coal entering the receiver 72 in successive columns or charges operates to expel the preceding columns or charges of coal entering the said receiver, and by this means the receiver is maintained in a free condition for practical operation during the entire movement thereof lengthwise of the vein or seam of coal being cut. After the machine has completed its run, or reached the end of the vein or seam, the motor 22 is reversed and

the hopper or hopper car 5 caused to return to the starting point and the receiver 72 and conveyor 68 adjusted to similarly cut the coal from the vein or seam immediately 5 above the location of the previous cut, and this operation is continued until the vertical extent of the vein or seam has been similarly operated upon. The conveyor 67 carrying the receiver 72 is then adjusted 10 to project the requisite distance from the hopper or hopper car 5 and the said receiver under this new adjustment is caused to again cut the coal from the vein or seam at a greater depth fully over the vertical extent of the 15 vein. This projected adjustment of the conveyor 68 and receiver 72 is continued until the maximum adjustment or projection is reached, and if a still deeper cut is permissible and required, the track rails 8 are 20 then moved closer to the mine wall and the vein or seam further cut in the same manner and by the same adjustments as when starting the first cut.

All of the movements and adjustments of 25 the conveyor 67 and receiver 72 are accomplished through the one shaft 25 and the mechanism carried by and connected thereto and to the various parts of the said conveyor and receiver. The rotation of the ring 111 30 with the cutting teeth 112, however, is independently controlled through the motor 103 and the shafts 107, 100 and 118 with their intermeshing gear devices and sprocket chain driving means, so that the manipulation 35 of the machine for the purposes of resetting the same to form new cuts may be carried on without actuating the cutting mechanism and permitting the latter to be properly set or adjusted before starting the cutting function of the said ring 111 and teeth 112. This independent control of the 40 cutting ring 111 and cutting teeth 112 will materially save power and render the cutting mechanism more easily controllable and also 45 avoid accidents that might ensue if the cutting mechanism continued to operate at times when the machine was returning to a starting point, or during other periods when it would be unnecessary to have the cutting 50 mechanism in operation.

The improved mechanism is very easily 55 operated and the mining of coal may be effected thereby at a materially reduced expense and the loading operation facilitated at the same time that the coal is cut from the vein or seam. It is also advantageous 60 to have the machine run on its own power and to provide for operatively distributing the power from one shaft, and by means of 65 which the mechanism is considerably minimized without in the least impairing the effectiveness of a machine of this class.

What is claimed as new is:

1. A machine of the class specified, comprising an enclosing receiver open at its

front end and provided with cutting mechanism around said open front end and forming a part thereof, the receiver being closed at its rear end, and means for moving the receiver and cutting means in a rectilinear path for cutting material from the face of a vein in a straight line throughout the length of the vein, the cut material being injected into and carried by the receiver in charges and expelled from the latter by subsequent incoming charges. 70

2. A machine of the class specified comprising a receiver with a closed outer portion and an open end having cutting means therearound to cause the material cut to pass 80 into and be carried by the receiver, and means for moving the receiver in a straight line throughout the length of the material cut and for operating and simultaneously 85 similarly moving the cutting means to cause the latter to have a straight line cutting action throughout the length of the wall of material cut.

3. A machine of the class specified, comprising a receiver having an outer closed side portion to move through the material cut and an open cutting end with cutting means extending around said end, and means for causing the receiver to travel in a rectilinear path the full length of the wall 90 of material cut and continue to cut and have the cut material delivered therefrom during its progress in a straight line throughout the extent of the wall of material engaged thereby. 100

4. A machine of the class specified, comprising a receiver having a forward open end, a rear closed end, an outer straight closed side and a discharge opening at the inner side, the receiver also having open cutting mechanism at the open end thereof, and means for causing the receiver and its cutting mechanism to move lengthwise of and cut material from a wall in a straight 105 line throughout the extent of the said wall 110 engaged thereby.

5. A machine of the class specified, comprising a receiver having a forward open end, a rear closed end, an outer straight closed side and a discharge opening at the 115 inner side, the receiver also having open cutting mechanism movable around the open end thereof, and means for causing the receiver and its cutting mechanism to move and cut material from a wall in a straight 120 line and in the same horizontal level throughout the extent of the said wall engaged by the receiver and cutting means.

6. A machine of the class specified, comprising a receiver having a front open end 125 and the remaining portion forming a carrying enclosure with an outer straight closed side and inner side discharge opening, the receiver being provided with open cutting mechanism at its open end and moving 130

therewith as a unit, and means for regularly moving the receiver and its cutting means as a unit in a straight line in a horizontal plane relatively to and in the face of a vein and having the cut material injected therewith and discharged from the said inner side discharge opening during the movement of the receiver.

7. A machine of the class specified, comprising an enclosing receiver having an open end provided with open cutting mechanism operable therearound, means for moving the receiver and its cutting mechanism as a unit in a rectilinear path in a horizontal plane, and means for vertically adjusting the receiver and its cutting means as a unit to different elevations to similarly operate relatively to the material to be cut.

8. A machine of the class specified, comprising a receiver having an open end with open cutting means mounted to operate around the open end of the receiver and uniformly movable with the receiver progressively in a straight line, a conveyor carrying the receiver at its outer end and onto which the cut material is discharged from the inner portion of the receiver, and means for uniformly moving the conveyor and the receiver carried thereby in a rectilinear path relatively to the material to be cut.

9. A machine of the class specified, comprising a receiver having an open end with open cutting means operably mounted thereon and uniformly movable with the receiver, a conveyor carrying the receiver at its outer end and onto which the cut material is discharged, means for uniformly moving the conveyor and receiver carried thereby in a rectilinear path relatively to the material to be cut and cause the receiver and cutting means to enter and move in a straight line in the material, and means for uniformly elevating the conveyor and receiver with its cutting mechanism to different elevations relatively to the material to be cut.

10. A machine of the class specified, comprising a tubular receiver having a front open end and into which the cut material is injected and retained at intervals and discharged therefrom by incoming charges of material, an annular rotary cutter at the open inlet end of the receiver and forming part of the latter, means for loosening the cut material injected into the receiver and discharging said material from the latter, and means for progressively moving the receiver with its cutter in a rectilinear path through the mass of material cut and received thereby.

11. A machine of the class specified, comprising a tubular receiver having an outer longitudinally straight side, a rear closed end, a discharge opening at its inner side and a front open end, an annular rotary

cutter mounted and operating on and around the said front open end of the receiver for cutting material from the face of a vein in columns which pass through the cutter into the receiver, means for loosening the cut columns in the receiver relatively to the vein from which they are cut, means for conveying the cut material away from the receiver, and means for moving the receiver and conveying means rectilinearly with relation to the vein from which the material is cut.

12. A machine of the class, specified, comprising a tubular receiver having a front open end and the remaining portion thereof closed except a discharge opening at the inner side thereof, cutting mechanism mounted and movable on the front open end of the receiver, means operating with the rear portion of the receiver for loosening the cut material injected therewith relatively to the vein or seam from which it is cut, and means for moving the receiver and its cutter in a rectilinear path in and throughout the full length of the vein or seam operated upon by the cutter and receiver, the successive charges of cut material entering the receiver forcing out the preceding charges therefrom.

13. A machine of the class specified, comprising a tubular receiver having a front fully open inlet end provided with an open cutter mounted and rotatable therearound and through which cut material passes into the receiver, conveying means connected to the receiver and including an endless conveying belt onto which the cut material from the receiver is continuously discharged during the cutting operation, and means for causing the tubular receiver and the conveying means to move rectilinearly relatively to the longitudinal direction of a vein of material to be cut and cause the receiver and cutter to progressively move in the vein in a straight line.

14. A machine of the class specified, comprising supporting means a receiver with an open end having a cutting means mounted on said end and forming part of the receiver, supporting means for the receiver, means for longitudinally projecting and retracting the receiver relatively to the supporting means, and means for moving the receiver and supporting means rectilinearly in relation to the material to be operated upon, the adjustment of the receiver relatively to the supporting means being effected while the latter is at rest.

15. A machine of the class specified, comprising supporting means, a receiver having cutting mechanism and associated with said supporting means, means for longitudinally projecting the material carrying receiver outwardly from or retracting it in relation to the supporting means to cut

material at different depths without re-setting the supporting means relatively to the material to be cut, and means for moving the receiver and supporting means relatively to the material to be cut, the adjustment of the receiver relatively to the supporting means being effected while the latter is at rest.

16. A machine of the class specified, comprising supporting means, a conveyor adjustable inwardly towards and outwardly from the supporting means in a straight line and having a material-carrying receiver fixed on its outer extremity and provided with cutting means, and means for moving the supporting means, conveyor and receiver as a unit rectilinearly in relation to the material to be cut, the conveyor and receiver being adjustable relatively to the supporting means while the latter is in a position of rest.

17. A machine of the class specified, comprising a hopper, a conveyor extending from one side of the hopper and adjustable longitudinally inwardly and outwardly with relation to the latter, a material-carrying receiver fixed on the outer extremity of the conveyor and having an open end provided with cutting mechanism movable thereon, and means for moving the supporting means, conveyor and receiver as a unit rectilinearly with relation to the material to be cut, the conveyor and receiver being adjustable relatively to the hopper while the latter is at rest.

18. A machine of the class specified, comprising a hopper provided with track wheels and also having means for discharging the contents of the same therefrom, a conveyor adjustably mounted on one side of the hopper and longitudinally movable inwardly from and outwardly towards the hopper side and material to be cut and having a receiver fixed on the outer extremity thereof and provided with cutting mechanism on one end thereof, and means for moving the hopper, conveyor and receiver as a unit in a straight line relatively to the material to be cut and also for causing the material cut to be discharged by the conveyor into the hopper regularly during the cutting operation, the conveyor and receiver being longitudinally movable with relation to the hopper while the latter is at rest.

19. A machine of the class specified, com-

prising a receiving hopper having means for discharging the contents thereof from one end, a conveyor movably associated with one side of the hopper and longitudinally adjustable inwardly and outwardly to modify the extent thereof with relation to said hopper side, the conveyor having a tubular enclosing receiver fixed on its outer extremity and provided with an open end around which cutting mechanism is operatively disposed, and means for moving the hopper, conveyor and receiver on the outer end of the latter as a unit in a straight line relatively to the material to be cut, the adjustment of the conveyor relatively to the side of the hopper being effected while the hopper is at rest.

20. A machine of the class specified, comprising a hopper mounted on track wheels and having means for discharging the contents thereof at one end of the same, a conveyor freely slidable in a straight line inwardly and outwardly with relation to one side of the hopper and also vertically movable to adjust the same to different elevations, an enclosing receiver having one open end fixed on the outer extremity of the conveyor and provided with cutting mechanism on and operable around said open end, and means for moving the hopper, conveyor and receiver as a unit in a straight line relatively to a vein from which material is to be cut.

21. A machine of the class specified, comprising a hopper mounted on track wheels and carrying motor and shaft mechanism geared to a part of the track wheels, a conveyor adjustable longitudinally inwardly and outwardly in relation to and carried by one side of the hopper and having a tubular enclosing receiver fixed on its outer extremity with one open end, the open end of the receiver being provided with cutting mechanism movable therearound, mechanical operating devices interposed between the said shaft and conveyor for controlling the adjustment of the latter and operable independently of the same for operating a part of the track wheels, and a motor mechanism and connections between the same and the cutting mechanism for independently starting and stopping the operation of the said cutting mechanism.

In testimony whereof I affix my signature.

FRANCIS K. HOLMESTED.
